[57] CLAIM

The ornamental design for a water pipe, as shown and
described.

DESCRIPTION

FIG. 1 is a front elevational view thereof the water pipe
showing my design, *the broken lines are for purposes of
illustration only and form no part of the invention*;
FIG. 2 is a right side elevational view thereof with the
opposite side view being a mirror image thereof, *the broken
lines are for purposes of illustration only and form no part
of the invention*;

FIG. 3 is a top plan view thereof, *the broken lines are for
purposes of illustration only and form no part of the inven-
tion*; and,

FIG. 4 is a perspective view thereof, *the broken lines are for
purposes of illustration only and form no part of the inven-
tion*;

The undisclosed bottom and rear views are unornamented.

1 Claim, 2 Drawing Sheets

Matter enclosed in heavy brackets [ ] appears in the
original patent, but forms no part of this reissue; matter
printed in italics indicates the additions made by reissue.
